Filed Oct. 9, 1974, Ser. No. 513,451

Term of patent 14 years

Int. Cl. D12—16

U.S. Cl. D12—205

FIG. 1.

FIG. 2.

FIG. 3.

FIG. 1 is a side elevational view of a spoked vehicle wheel showing my new design.

FIG. 2 is an end elevational view thereof.

FIG. 3 is a cross-sectional view thereof taken on lines 3—3 of FIG. 1.

The characteristic feature of my new design resides in the specific pattern formed by the five separate spoke groupings, wherein each grouping is comprised of eight spokes.

I claim:

The ornamental design for a spoked vehicle wheel, as shown and described.
